DESCRIPTION

FIG. 1 is a bottom perspective view of a linear luminaire, showing our new design;

FIG. 2 is a top perspective view thereof;

FIG. 3 is cross-sectional view taken from FIG. 5 thereof;

FIG. 4 is a top elevation view thereof;

FIG. 5 is a bottom elevation view thereof;

FIG. 6 is a front elevation view thereof;

FIG. 7 is a rear elevation view thereof;

FIG. 8 is a left-side elevation view thereof; and

FIG. 9 is a right-side elevation view thereof.

FIG. 10 is a bottom perspective view of another embodiment of a linear luminaire, showing our new design;

FIG. 11 is a top perspective view thereof;

FIG. 12 is a cross-sectional view taken from FIG. 14 thereof;

FIG. 13 is a top elevation view thereof;

FIG. 14 is a bottom elevation view thereof;

FIG. 15 is a front elevation view thereof;

FIG. 16 is a rear elevation view thereof;

FIG. 17 is a left-side elevation view thereof; and,
